DESIGN FOR A CLOTHES HANGER

Louise Sanders, Hoboken, N. J., assignor to Consolidated Molded Products Corporation, Scranton, Pa., a corporation of Delaware

Application February 7, 1946, Serial No. 126,334

Term of patent 14 years

(Cl. D80—8)

To all whom it may concern:

Be it known that I, Louise Sanders, a citizen of the United States, residing at Hoboken, in the county of Hudson and State of New Jersey, have invented a certain new, original, and ornamental Design for a Clothes Hanger, of which the following is a specification, reference being had to the accompanying drawing, forming part thereof.

I claim:

The ornamental design for a clothes hanger, as shown.

LOUISE SANDERS.
